UNITED STATES PATENT OFFICE.

FRANK C. KNAPIK AND JOHN S. KNAPIK, OF BALTIMORE, MARYLAND.

SPARK CONTROL AND TESTER.

Application filed July 18, 1925. Serial No. 44,429.

This invention relates to automobile engines and their electrical equipment.

More particularly the invention relates to a spark control tester for automobile engines.

One object of the invention is to improve the general construction of a device of this character.

A second object of the invention is to provide improved means for regulating the gap of the spark control.

A third object of the invention is to provide a novel device of this character wherein the spark gaps will be simultaneously adjusted.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a face view of the invention.

Figure 2 is a section on the line 2—2 of Figure 1.

Figure 3 is a rear view of the invention.

30 In the embodiment of the invention herein described there is provided a housing comprising a cylinder 10 having on one end a flange 11. In the rear end of this cylinder 10 there is secured an insulating disk

35 12 on the outer or rear side of which is cemented or otherwise secured an insulating plate 13. Through the plate 13 and bottom 12 extends a series of terminal members 14 having on their rear ends binding nuts 15.

40 Each of these members is provided with a collar 16 which fits in a recess 17 in the forward face of the plate 12, also each member is provided with a nut 18 which clamps the member in position.

45 Secured on the front flange 11 of the housing is a face plate 19, the same being held in position by screws 20.

Within the cylinder 10 is an insulating disk 21 in the center of which is an insulated disk having in its center a bushing 22 threaded internally to receive a screw 23 provided with a collar 24 which engages the inside of the front plate 19. In this disk is provided a series of openings 25 corresponding in number and position to the ter-

minals 18. In each of these openings is seated a bushing 26 having a separate dispositioned recess 27 on its rear side and provided on its front side with a pin 28 which seats within an opening 29 in the front plate 19. The screw 23 is provided with a turning knob 30 which is secured on the projecting end thereof.

The casing 10 is grounded by a suitable connection and to each of the terminals 14 is connected one wire leading to a respective spark plug. Now by turning the knob 30 the plate 21 is moved inwardly or outwardly with respect to the terminals 14 so that a spark is established, first between the respective terminal 14 and the bushing 26 and then between the bushing 26 and the side of the opening 29. Thus the operator can observe closely the conditions prevailing and determine which plug is not operating.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

In a device of the kind described a housing, an insulating plate supported at one end of said housing, a series of electrodes carried by said insulating plate, a second insulating plate movable in said housing toward and from the first insulating plate, means to move the second insulating plate toward and from the first insulating plate, a second series of electrodes carried by the second plate and positioned in opposition to the first electrodes, a fixed conductive plate carried by said housing and having the second series of electrodes spacedly positioned relative thereto whereby movement of the movable plate will move the second series of electrodes toward the first series and increase the space between the second series and the fixed conductive plate.

In testimony whereof we affix our signatures.

FRANK C. KNAPIK.
JOHN S. KNAPIK.
